J. T. McCOURT

GAS BURNER

Filed June 10, 1926

UNITED STATES PATENT OFFICE.

JOHN T. McCOURT, OF LOS ANGELES, CALIFORNIA, ASSIGNOR OF ONE-HALF TO RALPH I. GUY, OF LOS ANGELES, CALIFORNIA.

GAS BURNER.

Application filed June 10, 1926. Serial No. 115,052.

This invention relates to improvements in gas burners and more particularly to a type of burner in which the gas and the air are not mixed until after the ejection of the gas from the nozzle, and arranged so as to supply both air and gas under pressure to the mixing area, whereby a maximum temperature may be obtained with a minimum pressure, and particularly adapted for use in connection with blast furnaces for reducing ore.

Other objects of invention will appear in the specification hereinafter following, in which a preferred form of device is described.

I have shown said preferred form of device in the accompanying drawing, in which:

Fig. 1 is a side elevation of the assembled gas burner.

Fig. 2 is a sectional elevation of the same.

Fig. 3 is a rear end view thereof.

Fig. 4 is a rear view of the body closure for supporting the nozzle in operative position.

Fig. 5 is a side view of the same; and

Fig. 6 is a rear view of a special form of cap adapted for use in my burner.

Briefly described, my improvements consist in the provision of a burner body as at B, in the form of an elbow with a cap C attached to the horizontal portion 1 thereof, and an air supply pipe P attached to the vertical portion 2. A gas supply tube G is centrally mounted in the body B and is provided with a nozzle N and an inlet I. Said tube is suitably supported in an end closure E by means of a ring R, as shown in Fig. 2.

The portion 1 of the body B is externally threaded to receive a cylindrical portion 3 of cap C, and said cap has a conical portion 4 of cylindrical cross section forwardly of the portion 3 thereof, with a central opening O in its end, and a plurality of spirally or angularly formed ribs r, r, etc., internally thereof as shown in Fig. 2. A plurality of lugs 5, 5, may be provided on the exterior of cap C whereby said cap may be threaded onto and removed from the body B.

The gas supply tube G is centrally supported in the body B and is provided with an enlarged portion 6 within which is a gas expansion chamber g. Forwardly of said expansion chamber is a tubular nozzle N having a gas passage 7 therein of smaller area than the chamber g. Said nozzle extends substantially forwardly into the air chamber 2 within the body B, to which air is supplied

through the vertical passage 8 in the portion 2 of said body from pipe P. Member G also has a right angularly formed inlet pipe I adapted to be suitably attached to a gas supply pipe.

The rear wall 9 of body B is provided with a threaded opening into which an end closing member E is threaded, for the purpose of detachably supporting the member G in operative position in the body B. Said member E has threads 10 on the periphery of the flange portion 11 thereof, for attaching the same in position in the body, and the flange portion 11 is provided with lugs 12, 12 whereby the same may be attached to and detached from said body. The member E has an extended boss 13 with a bore 14 extending longitudinally therethrough to receive a portion 15 of member G, and the outer end of said boss abuts the shoulder 16 formed on the large portion 6 of the member G. The adjacent portions of the boss 13 and the portion 6 of member G are externally threaded to receive an internally threaded ring R for holding the member G in position on the member E and centrally disposed in the member B.

The nozzle N is extended forwardly into the cap C for a sufficient distance so that the gas ejected from said nozzle will impinge on the inwardly projecting ribs r, r, etc., and cause a whirling or eddying of the gas as the same is ejected from the opening O of the cap C, also the air from the air chamber A which is admitted under pressure from pipe P will mix with the gas internally of the cap C and will be set in motion by means of the ribs r, thus effecting a more perfect mixture of the gas and air than would otherwise be possible.

Either artificial or natural gas may be employed for use as a fuel in my burner, and relatively low gas pressures may be used for ejecting the gas from the nozzle N, due to the fact that the whirling of the gas and air during the mixing process forwardly of the nozzle serves to create a partial vacuum in front of the nozzle and thus produce sufficient suction to induce the flow of gas from the nozzle when the pressure of the gas is very low.

It will be obvious that by increasing the air pressure in the chamber A the suction of the gas from the nozzle N will be correspondingly increased so as to overcome any deficiency in pressure in the natural or artificial pressure of the gas.

It will be understood that while I have

shown only a preferred form of my invention for the uses stated, the same may be modified to meet other uses without departing from the spirit of my invention or enlarging the scope thereof beyond that of the appended claims.

What I claim is:

1. A gas burner comprising a body member having a cylindrical air chamber therein, an air inlet thereto, a cylindrical cap detachably held on said body member and provided with a frusto-conical end portion and a central opening therein, a plurality of internally formed spiral ribs on said frusto-conical portion, an end closure in the rear wall of said body detachably held therein, a gas supply tube detachably held on said closure and provided with a nozzle centrally positioned in said air chamber, said gas supply tube having an intermediate expansion chamber rearwardly of said nozzle, and a gas inlet for supplying gas to said expansion chamber.

2. A gas burner having a body with an air chamber therein for receiving air under pres-

sure, an air inlet communicating therewith, and an outlet, a cap encompassing said outlet and provided with a conical end portion having a central opening therein forming an outlet for the air and gas, a plurality of internally formed spiral ribs on the conical portion of said cap for imparting a whirling motion to the mixture of gas and air, a gas supply tube centrally mounted in said body and axially aligned with said cap, said gas supply tube having a nozzle positioned within said body, a gas inlet externally of said body, an intermediate enlargement provided with an expansion chamber therein and in communication with said nozzle and said inlet, said body having a threaded opening in the rear wall thereof aligned with the opening in said cap, a closure 40 detachably held in said opening and provided with a central bore for receiving said gas supply tube, and a threaded ring embracing adjacent portions of said closure and said tube for detachably supporting said tube in position.

JOHN T. McCOURT.
